UNITED STATES PATENT OFFICE.

FRANK D. MARCH, OF CAMBRIDGE, MASSACHUSETTS, ASSIGNOR TO THE STANDARD RIVET COMPANY, OF CONCORD, NEW HAMPSHIRE.

DESIGN FOR AN ORNAMENTAL RIVET.

SPECIFICATION forming part of Design No. 29,699, dated November 22, 1898.

Application filed January 29, 1898. Serial No. 668,492. Term of patent 14 years.

To all whom it may concern:

Be it known that I, FRANK D. MARCH, a citizen of the United States, and a resident of Cambridge, in the county of Middlesex and State of Massachusetts, have invented and produced a new and original design for an Ornamental Rivet, of which the following is a specification.

Figure 1 is a perspective view of an ornamental rivet illustrating my design. Fig. 2 is a top or plan view thereof, and Fig. 3 is a diametral section of the rivet to more clearly show the raised head.

The leading feature of my design for an ornamental rivet consists in a raised head having prong-like or barbed legs extending from the periphery of the head and substantially at right angles to the plane of its base diametrically opposite each other and in parallelism.

The ornamental rivet, as herein illustrated, comprises a raised head a , having extended from its periphery a' prong-like or barbed legs a'' , said legs being shown as spear-shaped at their ends, as a'' , and substantially at right angles to the plane of the base of the head. As shown, the legs are diametrically opposite and in substantial parallelism.

Having fully described my invention, what I claim, and desire to secure by Letters Patent, is—

The design for an ornamental rivet substantially as herein shown and described.

In testimony whereof I have signed my name to this specification in the presence of two subscribing witnesses.

FRANK D. MARCH.
